UNITED STATES PATENT OFFICE.

JOHN HAYWOOD COMPTON, OF LONDON, ENGLAND.

EXPRESSIVE-TOUCH ACTION FOR ORGANS AND THE LIKE INSTRUMENTS.

Application filed August 17, 1921. Serial No. 493,090.

(GRANTED UNDER THE PROVISIONS OF THE ACT OF MARCH 3, 1921, 41 STAT. L., 1313.)

To all whom it may concern:

Be it known that I, JOHN HAYWOOD COMPTON, a subject of the King of Great Britain and Ireland, residing at London, England, have invented certain new and useful Improvements in Expressive-Touch Actions for Organs and the like Instruments (for which application has been filed in Great Britain, Patent No. 169,244, filed 10 June 18, 1920), of which the following is a specification.

The object of this invention is to provide a new and improved mechanism for organs and the like instruments whereby the number or selection of pipes or other sound producing means operated by any key shall be determined by the force with which the key is struck by the finger of the performer, thus furnishing the organ with a key-board expression comparable with that of the pianoforte.

Various devices with this object have been proposed wherein hammers actuated by the keys in the manner of a pianoforte operate directly on the pallet or pallet connections of the sounding device. The present invention however has reference especially to electric or electropneumatic actions.

In one known mechanism intended for use with actions of this nature the key is jointed at one end to a weighted lever adapted to make contact with one or more contact plates and close one or more electric circuits according to the force with which the key is struck the varying effect being dependent upon the extent to which the inertia of the weighted lever extends a spring that normally supports it.

In another known type of mechanism for the same purpose the varying effect depends again upon a weighted contact-making lever connected to the key but in this case upon the momentum of the lever, and the extent to which the key throws it out of its normal position.

My invention provides a greatly increased range of expression combined with an agreeable key touch and satisfactory repetition.

To carry it into effect, according to one method, I use a hammer (operated by means of a train of mechanism in the manner of a piano key action, or by other suitable

means) which when the key is depressed directly or indirectly moves a contact carrying member, displacing it more or less according to the force of the blow, and thereby closing one or more electric circuits, each of which is operatively connected with a sound producing means in the organ.

In one form of mechanism suitable for use in an electro-pneumatic organ, a manual key when depressed operates the normal mechanism of the organ in known manner. On the free end of the key is carried suitable means for actuating a pivoted hammer lever, which is tilted when the key is depressed. The hammer lever is normally held up by the action of a spring on the end of the lever remote from the hammer head.

If the key is depressed gently, the hammer head cannot be brought down beyond a definite position, as any depression of the key beyond a certain point merely releases the hammer. If the key be more forcibly struck, the momentum of the hammer head will carry it lower, and it will then displace the contact carrying lever, pivoted below it, more or less in proportion to the force of the blow. The contact lever is pivoted to move in the same vertical plane as the hammer lever and carries on its side a contact piece which is adapted to make electrical contact successively with a number of wires, each of which is connected with an electro-pneumatic note sounding means in the organ. According to the extent of depression of this contact lever the proportionate number of electrical circuits will be closed, and a corresponding number of note sounding means will be put in operation. The total volume of sound produced will therefore vary more or less as the force with which the key is struck.

In order to control the extent of the displacement of the contact lever under the hammer blow I may use a spring friction device comprising a spring shaped to the arc of a circle and bearing on the free end of the contact making lever and capable of being accurately adjusted in position upon a fixed support, or I may mount the friction springs of all the contact levers upon a common shaft capable of being rocked at will to vary the displacement of

the contact lever by a given hammer blow, or to hold the contact lever in a given position after displacement.

Suitable means are provided for raising the contact lever at will after depression (and without raising the key) without however bringing it out of contact with all the circuits, but only so as to reduce the volume of sound.

10 Instead of the hammer operating the contact lever by striking it directly it may operate it through a pneumatic device comprising a pallet adapted to be depressed by the hammer and admit compressed air in quantity varying with the blow of the hammer to a wind motor which moves the contact carrying element into contact with one or more contact wires as before. An exhaust pallet, normally open, is closed on depression of the key and can be kept closed when required to give a "sostenuto" effect and prevent the motor deflating. Means are provided for increasing or reducing the supply of compressed air if desired after a key has 25 been depressed and so increasing or reducing the volume of sound.

All the moving parts are preferably of light construction and thus the initial attack and repetition may be perfectly adjusted and the key touch will be light and agreeable. With each contact lever may be associated a considerable number of contact wires and thus a very large range of expression is possible.

30 35 The invention is illustrated in the accompanying drawings.

Fig. 1 is a sectional side elevation of a complete "expressive touch" mechanism for one key.

40 Fig. 2 is a similar view of the hammer actuating means but in the position it occupies when the manual key is fully depressed.

45 Fig. 3 is a view of an alternative form of the spring device for controlling the extent of movement of the lever carrying the contact plate.

50 Fig. 4 is a view of a pneumatic device suitable for use in conjunction with the new hammer action.

55 Fig. 5 is a detail perspective view showing how the varying contact is formed.

Referring to Fig. 1 *a* is the usual manual key maintained in its normal position by a spring *b* and adapted when depressed to operate any suitable note sounding mechanism not shown. At the rear end of key *a* is an L-shaped jack *d* pivoted at *e* in known manner and held with its lower end against a stop and so disposed as to engage with one of its ends beneath a projection *f* on the hammer butt *g*.

60 When the key *a* is depressed jack *d* is lifted together with hammer butt *g* so that the hammer head *h* is moved in a downward direction.

The parts are so adjusted that when the key *a* is depressed past a certain point the jack *d* will escape past the projection *f* on hammer butt *g* in a similar manner to the corresponding parts of a piano action, thus 70 allowing the parts to assume the relative positions shown in Fig. 2 where the jack has escaped and moved to the right against the spiral spring *i*.

Reverting to Fig. 1 *j* is a lever pivoted at 75 *k* and carrying a contact plate *l* adapted to engage successively the contact wires *m*, *m'*, *m''*, etc., when the rear end of the lever *j* is depressed by the stroke of the hammer head *h*. The contact wires *m*, *m'*, etc., and the electric circuit connectors are suitably joined to the electro-pneumatic note sounding member *P* in the organ as shown in Fig. 1.

The extent of depression of the lever *j* 85 and consequently the number of contact wires engaged, will vary with the force of the blow.

n is a movable bar operated by pedal or other suitable means, adapted to move upwards and to move lever *j* towards its normal position and consequently to diminish the volume of sound either gradually or suddenly while the key is kept in the depressed position. *o* is a stud attached to the key *a*, 90 its office being to restore lever *j* to its normal position when the key is released.

q is a spring mounted on a fixed support *x* which by friction against the end of lever *j* will govern the extent of its downward travel. An alternative arrangement for this purpose is shown in Fig. 3 in which spring *q'* is attached to a shaft *r* (common to all the springs *q'*) adapted to be rotated by means of a pedal or other suitable device 100 whereby the pressure of the springs *q'* upon their respective contact levers may be regulated. Thus the pressure may be increased to such an extent that the lever *j* will make scarcely any movement even though the hammer blow be very heavy, or the pressure may be increased after the hammer blow has been delivered so that the levers are retained in the depressed position even after the keys are released, thus furnishing a useful "sostenuto" effect.

In the construction illustrated the keys *a* will also remain depressed as long as the levers *j* are held down.

Fig. 4 illustrates a pneumatic device. 120 The hammer actuating mechanism is as above described but the hammer head *h* instead of directly striking the contact lever strikes a stud *s* operatively connected with a pallet *t* in a chamber *6* containing compressed air which pallet is normally held by a spring *u* in a position closing the air channel *v*.

When stud *s* is struck by the hammer head *h* compressed air is admitted by the mo- 130

mentary displacement of pallet *t* to the channel *v* and motor *w* contained in chamber 7 and the amount of air so admitted will vary with the force of the hammer blow.

- 5 *j* is the contact lever attached to the motor *w* and carrying contact plate *l*. Lever *j* is normally held in the position shown by a spring *x*. On air entering channel *v* and motor *w* lever *j* is depressed and electrical contacts are made to a greater or less number according to the amount of air admitted by pallet *t* and the consequent inflation of motor *w*.

6 *y* is an exhaust pallet from motor *w*, normally raised, but lowered by the depression of the key. *z* is a "sostenuto" rail which when raised by suitable means closes all the exhaust pallets *y* thus preventing the immediate exhausting of the motors *w* even 20 when their respective keys are released.

7 and 4 and 3 and 5 are valves and regulating screws therefor whereby the volume of sound may be increased or decreased after the key has been struck.

- 25 8 *By opening valve 2 by means of a pedal or other device more compressed air from chamber 6 will be admitted to channel *v* and motor *w* the rate of flow of air being controlled by regulating screw 3, and thus 30 the lever *j* will be further depressed and the number of electrical contacts and consequently the volume of sound increased.*

When it is desired to decrease the volume of sound valve 4 is opened and compressed air allowed to escape from motor *w* by channel *v* even though the key is not released and the pallet *y* is still closed.

- 35 Instead of using a hammer member *h* I may arrange the movable contact carrying member *j* so that it is moved directly by the inner end of the manual key; in this case also the contact member *j* will be displaced to a greater or less extent according to the force with which key *a* is depressed. 40 the member *j* not being jointed to *a* or connected therewith but adapted to be struck up or down and to move under its own momentum to a greater or less extent.

I claim:

- 50 1. A musical instrument having sound producing means, an operating key mechanism, a control for said sound producing means, a hammer supported independently of said key mechanism but having engagement therewith, and a movable member upon release of said hammer from said key to be struck by said hammer and form a varying contact with said control mechanism, depending upon the rapidity with 55 which the key mechanism moved before the release of said hammer.

2. A musical instrument having sound producing means, an operating key mechanism, a control for said sound producing means, a hammer supported independently 60

of said key mechanism but having engagement therewith, a movable member upon release of said hammer from said key to be struck by said hammer and form a varying contact with said control mechanism, depending upon the rapidity with which the key mechanism moved before the release of said hammer, and means for regulating the volume of sound produced. 70

3. An instrument of the class described 75 comprising a key operating mechanism, a sound producing means, a plurality of controls associated with said sound producing means, a trip hammer releasably engaging said operating mechanism, and means upon 80 release of said hammer from said operating mechanism to be struck by said hammer and brought into varying contact with said controls depending upon the rapidity with which the operating mechanism moved before the release of said hammer. 85

4. In a musical instrument having sound producing means, the combination with a key mechanism, a plurality of electric controls associated with said sound producing means, a trip hammer engaging said key mechanism and adapted upon release therefrom to strike said lever and bring the latter into varying contact with said sound producing means. 95

5. A musical instrument having in combination a key mechanism, a support having a hammer pivotally secured thereto, said hammer normally engaging said key mechanism, a lever pivoted to said support beneath said hammer, said lever provided at one end with a contact plate, a fixed support below said lever, a plurality of contact members extending through said fixed support to form a varying contact with 100 said contact plate when the lever is struck by said hammer. 105

6. A musical instrument having in combination a key mechanism, a support having a hammer pivotally secured thereto, said hammer normally engaging said key mechanism, a lever pivoted to said support beneath said hammer, said lever provided at one end with a contact plate, a fixed support below said lever, a plurality of contact members extending through said fixed support to form a varying contact with said contact plate when the lever is struck by said hammer, and means projecting from 110 said fixed support for regulating the downward movement of said lever. 115

7. A musical instrument having in combination a key mechanism, a support having a hammer pivotally secured thereto, said hammer releasably engaging said key mechanism, a lever pivoted to said support beneath said hammer, said lever provided at one end with a contact plate, a fixed support below said lever, a plurality of contact members extending through said fixed support 120

125

130

port to form a varying contact with said contact plate when the lever is struck by said hammer, springs in said fixed support to limit the downward movement of said lever and means between said lever and said fixed support for returning the lever to its normal position.

8. A musical instrument of the class described having in combination a support, a hammer pivotally secured to the top of said support, a lever pivoted to the bottom of said support having a contact plate at the end thereof, a fixed support below said lever provided with a plurality of contact members, to be brought into varying contact with said contact plate when the lever is struck by said hammer.

9. A musical instrument having in combination a key, a jack pivoted to said key, a support having a hammer pivotally secured thereto, said hammer normally engaging said jack, a lever pivoted to said support and provided at one end with a con-

tact plate, a fixed support below said lever having a plurality of contact members, and means upon depression of said key for tripping said jack and actuating said hammer for forming a varying contact between the contact plate and the contact member for the purpose specified.

10. A musical instrument having in combination a key, a pivoted member positioned to be turned about its pivot by the depression of the key, with varying rapidity according to the rapidity with which the key is depressed, a plurality of fixed contacts, a movable contact member positioned to be struck by the pivoted member when the latter is turned about its pivot, and to be moved by the stroke of the pivoted member to an extent varying according to the rapidity of that stroke and make contact with a varying number of the fixed contacts according to the rapidity of the stroke of the pivoted member.

JOHN HAYWOOD COMPTON.
